UNITED STATES PATENT OFFICE.

BENJAMIN CALVEN BARTLEBAUGH, OF WHEELING, WEST VIRGINIA.

GAS HEATER.

Application filed December 15, 1924. Serial No. 756,070.

To all whom it may concern:

Be it known that I, BENJAMIN CALVEN BARTLEBAUGH, a citizen of the United States, residing at Wheeling, in the county of Ohio and State of West Virginia, have invented certain new and useful Improvements in Gas Heaters; and I do declare the following to be a full, clear, and exact description of the invention, such as will enable others skilled in the art to which it appertains to make and use the same.

My invention relates to improvements in heaters such as those which are commonly operated by gas, and it is the object of the invention to provide a generally improved construction which will be rather simple and inexpensive, yet will be highly efficient and durable.

With the foregoing and other objects in view, the invention resides in the novel subject matter hereinafter described and claimed, the description being supplemented by the accompanying drawings.

Figure 1 is a perspective view of a gas heater constructed in accordance with my invention.

Figure 2 is a vertical transverse sectional view.

Figure 3 is a horizontal sectional view as indicated by line 3—3 of Fig. 2.

Figure 4 is a vertical longitudinal section substantially on line 4—4 of Fig. 2.

Figure 5 is a perspective view with the air heating jacket and other parts removed.

Figure 6 is a perspective view of a portion of the fire wall.

Figure 7 is a perspective view of one of the members which close the spaces between inner and outer side walls and also mask the inner surfaces of the innermost of said walls.

Figure 8 is a perspective view of the burner.

Figure 9 is a disassembled perspective view showing the preferred manner of constructing the front portion of the jacket top.

In the drawings above briefly described, the numeral 1 designates a horizontal base plate which is preferably provided with downturned flanges 2, to which appropriate legs 3 are secured. Rising from the rear edge portion of the base 1, is a vertical back wall 4, and extending forwardly from the vertical ends of this back wall are two opposed side walls 5, said side walls being spaced inwardly from the ends of the base

1 and being preferably provided at their lower ends with angle metal bars 6 which are secured by bolts or the like 7, to the base. The upper ends of the side walls 5 are rearwardly inclined, and a similarly inclined top 8 rests on said inclined ends and extends forwardly therefrom, said top preferably having downwardly bent flanges 9 riveted, bolted or otherwise secured to the outer sides of the walls 4 and 5. The base 1, back wall 4, opposed side walls 5, and top 8, co-operate in forming a burner-containing casing which is open at its front. Disposed horizontally in the lower portion of this casing, is a burner 10 which is preferably of quadri-cylindrical form in transverse section, this burner being provided with an appropriate internal gas distributor 11, and with a gas supply pipe 12 having the usual air mixer 13. For securing the burner in place, I have provided it with a pair of forwardly projecting, C-shaped brackets 14 whose lower arms are secured to the base 1 by bolts or the like 15, the upper ends of these brackets having a function to be hereinafter described.

A fire wall 16 is mounted in the casing behind the burner 10, said fire wall consisting of a lower vertical section 17, an upper vertical section 18, and a horizontal intermediate section 19 which rearwardly offsets the section 18 from the section 17. The ends of all of these sections are provided with laterally bent flanges 20 so that they are transversely stiffened against bending or warping, and at least two of these flanges are instrumental in securing the fire wall in the casing, rivets 21 being shown, passing through the uppermost of said flanges and through the opposed side walls 5. The upper portion of the lower fire wall section 17, is preferably formed with a plurality of perforations 22 which lead directly over the burner 10, and the contiguous portion of said burner is by preference provided with a multiplicity of openings 23 which produce substantially a solid wall of flame immediately in front of the perforations 22. Thus, all air and unburnt gases passing through these perforations must immediately come in direct contact with this sheet or wall of flame, to be immediately consumed. For admitting air behind the fire wall 16, a series of openings 24 are formed in the base 1.

An inclined baffle plate 25 is secured in the

casing, in downwardly spaced relation with the top 8 thereof, said baffle plate extending over the fire wall 16, in spaced relation with the latter, and having its rear edge portion 5 directed downwardly as at 26, in a plane spaced rearwardly from said fire wall. The front edge of the baffle plate 25 is rearwardly spaced from the front edge of the top 8. By this relation of parts, all unburned gases 10 rising from the burner 10 are caught either by the top 8 or the baffle plate 25 and are by these parts directed to the space behind the fire wall 16, so that they can mix with the air from the openings 24 and pass through the 15 perforations 22 to be consumed by the solid wall of flame burning at the burner openings 23. Thus, the poisonous gases which would otherwise escape, are absolutely consumed and there is no danger from using the heater 20 even in poorly ventilated rooms.

An air heating jacket is provided around the casing above described. This jacket includes a vertical back wall 27 which is rearwardly spaced from the rear flange 2 of the 25 base 1. Extending forwardly from the vertical edges of this back wall 27, are two opposed side walls 28 whose lower ends may well be secured against the endmost of the flanges 2, by bolts or the like 29. Between 30 these walls 28 and the side walls 5, the base 1 is formed with air inlet openings 30. A top is mounted on the walls 27 and 28 and this top preferably comprises a back horizontal section 31 and a front rearwardly inclined section 32, the former having hot air escape openings 33. Both sections 31 and 32 are preferably provided with nickel-plated angle metal bars 34 which are suitably secured thereto and lap upon the outer sides 40 of the walls 28, to which they may be connected by bolts or other suitable fasteners 35, passing through the angle metal bars of the two top sections. The section 32 is also by preference tied to the top 8 of the burner 45 containing casing, by bolts 36, and spacing lugs 37 may well be struck upwardly from said top, to prevent downward springing of the section 32, when the bolts 36 are tightened. The upper and lower edges of the top 50 section 32 and the front edge of the section 31 are preferably equipped with nickel-plated finishing strips having rolled edges 38 which give a very attractive appearance to the heater. These finishing strips may be 55 bolted or otherwise secured in place, as will be readily understood.

Two vertically elongated members 39 are employed to close the spaces between the front edges of the two sets of side walls 5 and 28. These closure members are preferably formed of a first class grade of sheet metal as is also true of the entire jacket construction. The burner containing casing and base however may be of a cheaper grade of 60 metal which does not have an attractive

finish, as all parts of this inner casing are obscured from view. The inner edges of the members 39 are provided with rearward substantially rectangular extensions 40 which contact with the inner sides of the walls 5. 70 and mask the portions of these walls in front of the fire wall 16, and the outer edges of the members 39 may well be provided with rearwardly projecting flanges 41 to contact with the inner sides of the walls 28. 75

The members 39 and the adjacent edges of the walls 5 and 28, are rearwardly spaced to some extent from the front flange 2 of the base 1, and secured to this flange, is a horizontal finishing strip 42 whose ends may 80 well be bent rearwardly and inserted between the base and the side walls 28. Resting upon this finishing strip 42, is a horizontal sill plate 43 which is preferably nickel-plated and provided with a rolled front 85 edge. A portion of this sill plate extends rearwardly to the burner 10 and rests on the upper ends of the brackets 14, the latter forming supporting ledges for said plate, as will be clearly understood from Figs. 2 and 90 8. A suitable number of bolts or the like 44 pass through the base and the sill plate, to secure the latter in place.

It will be seen from the foregoing, that while the casing is being heated by the burner and all unburned gases are being consumed by said burner, an upward current of air will take place between the casing and the jacket, so that such current will be highly heated. The air enters the jacket near 95 the floor and by taking the cold air from this location and effectively heating it, great efficiency is obtained.

As excellent results have been obtained from the construction shown and described, 105 it may well be followed. However, within the scope of the invention as claimed, numerous modifications may be made.

I claim:

1. A heater comprising a casing having a 110 rearwardly inclined top and an open front, a burner in the lower portion of said casing spaced forwardly from the back wall thereof, a fire wall behind said burner having openings leading over the same to permit passage of unburnt gases and air to the burner flame to be immediately consumed, the casing being provided with an air inlet behind said fire wall, and a rearwardly inclined baffle plate in the casing spaced downwardly from said inclined top and upwardly from said fire wall, the front edge of said baffle plate being rearwardly spaced from the front edge of said top, and the rear edge of said baffle plate being turned downwardly 115 in rearwardly spaced relation with said fire wall. 120

2. A heater comprising a leg-supported base, a back wall rising from said base, a pair of opposed side walls extending for 125 130

- wardly from the ends of said back wall and spaced inwardly from the ends of the base, the latter having air inlet openings at the outer sides of said side walls, a top connected with said walls and co-operating with the same and the base in forming a casing; a burner in said casing for heating the same; and a jacket around the casing, said jacket comprising a back wall rearwardly spaced from the corresponding wall of the casing and also rearwardly spaced from the base to admit air, a pair of opposed side walls spaced outwardly from the first named side walls beyond said openings, a top spaced above the casing top and having heat escape openings, and closures for the spaces between the front edges of the two sets of side walls.
3. A structure as specified in claim 2; said closures having flat rearward extensions contacting with and masking the inner sides of the first named side walls.
4. A heater comprising a burner containing casing having an open front and opposed side walls extending thereto, a jacket for the casing having side walls spaced outwardly from the first named side walls, and closures for the spaces between the front edges of the two sets of side walls,
5. A heater comprising a casing having a base and formed with an open front, a finishing strip secured along the front side of said base and rising therefrom, a sill plate resting on said finishing strip and projecting rearwardly therefrom, a burner secured in the casing and having a ledge upon which the rear edge of said sill plate rests, and fastening means tying said sill plate and said base together.
6. A heater comprising a casing having a base and formed with an open front, a finishing strip secured along the front side of said base and rising therefrom, a sill plate resting on said finishing strip and projecting rearwardly therefrom, a burner in the casing having C-shaped brackets forwardly projecting under and in contact with said sill plate, means securing said brackets to the base to anchor the burner, and means tying said sill plate and said base together.

In testimony whereof I have hereunto affixed my signature.

BENJAMIN CALVEN BARTLEBAUGH.
